UNITED STATES PATENT OFFICE.

FRANK H. FARMER, OF CLEVELAND, OHIO, ASSIGNOR TO THE WHITE MOTOR COMPANY,
OF CLEVELAND, OHIO, A CORPORATION OF OHIO.

RADIATOR SUSPENSION.

1,322,683.

Specification of Letters Patent. Patented Nov. 25, 1919.

Application filed March 11, 1919. Serial No. 281,982.

To all whom it may concern:

Be it known that I, FRANK H. FARMER, a citizen of the United States, residing at Cleveland, in the county of Cuyahoga and 5 State of Ohio, have invented a certain new and useful Improvement in Radiator Suspensions, of which the following is a full, clear, and exact description.

The object of this invention is to provide 10 simple and inexpensive means for so supporting the radiator of a motor car or truck upon the chassis frame that said radiator will be very largely relieved from the strains to which it would be subjected if rigidly 15 connected to said chassis frame.

The invention consists in the construction 20 and combination of parts shown in the drawing and hereinafter described and pointed out definitely in the appended 25 claims.

In the drawing, Figure 1 is a front elevation of the radiator, a side member of which is partly broken away. This figure also shows in section the two side members of 30 the chassis frame; Fig. 2 is a side elevation of the lower part of one side member of the chassis frame, and shows also a part of the side member of the chassis frame; and Fig. 3 is an enlarged front elevation, partly 35 broken away, of a part of one side of the radiator.

Referring to the parts by reference characters, 20, 20, represent the two side members of the chassis frame of a motor car. 35 10, 10, represent the two vertical side frame members of the radiator structure, which radiator structure, except in the particulars hereinafter specifically referred to, may have any suitable construction. Each side frame 40 member is a casting, and it is cast with two laterally extended horizontal shelves 12 and 14 which overhang the associated chassis frame member, and are arranged a suitable distance the one above the other. It is also 45 formed with two laterally extended vertical flanges 16 at the front and rear edges of said frame member which flanges extend from the shelf 12 and the shelf 14 and a suitable distance above the latter.

50 21 represents a spring seat plate which is secured upon the top of each of said frame members 20 and may be regarded as a part of it. Two compressed coil springs 15 are supported on this spring seat plate, and pass 55 through holes 12^a in the bottom shelf 12 and

engage at their upper end with the under side of the shelf 14.

A stud 25 passes vertically through the horizontal flange 20^a of the chassis frame member through a hole in the spring seat plate 21, and through holes in the two shelves 12 and 14, said stud having a sliding fit in the last mentioned holes. It has a head 26 on its lower end which engages the under side of said chassis frame member 60 20. A coil spring 17 embraces this stud above the shelf 14 and is compressed between said shelf and a spring seat plate 18 which is held in place by a nut 19 which screws onto the upper end of said stud. The two 65 springs 15 yieldingly support the side of the radiator with which they are associated, and hold the shelf 12 thereof a suitable distance above the spring seat plate 21. The spring 17 yieldingly resists upward movement of 70 the radiator with respect to the chassis frame. The radiator therefore is yieldingly restrained from movement in either direction but is permitted to move in either direction as circumstances may be required, and 75 to an extent to enable the springs to absorb the shock which might otherwise be transmitted to the radiator frame. The stud 26 acts as a guide for the radiator frame member in the movement of the latter. The 80 flanges 16 help to protect the springs from 85 accidental injury.

Having described my invention, I claim:

1. The combination with the chassis frame of a motor car, of a radiator having at each 90 side a frame member on which are two laterally extended horizontal shelves which overhang a side member of the chassis frame, two compressed coil springs which are supported on the side member of the chassis 95 frame and pass through holes in the bottom shelf and engage the upper shelf, a stud having on its lower end a head which engages said chassis frame and which passes through the chassis frame and through both 100 shelves, a spring seat secured to said stud near its upper end, and a coiled spring which embraces said stud and is compressed between the upper shelf and the said spring seat. 105

2. The combination with the chassis frame of a motor car, of a radiator having at each side a cast frame member on which are two integral horizontal laterally extended shelves which overhang the adjacent side 110

member of the chassis frame and two integral vertical flanges which extend between and are connected with said horizontal shelves, two compressed coil springs which are supported on the side member of the chassis frame and pass through holes in the bottom shelf, and engage the upper shelf, a stud having on its lower end a head which engages said chassis frame and which passes

through the chassis frame and through both shelves, a spring seat secured to said stud near its upper end, and a coiled spring which embraces said stud and is compressed between the upper shelf and the said spring seat.

In testimony whereof, I hereunto affix my signature.

FRANK H. FARMER.
